CLAIM

The ornamental design for a casserole dish cover or the like, substantially as shown.

DESCRIPTION

FIG. 1 is a top perspective view of the casserole dish cover or the like showing our new design;
FIG. 2 is a bottom perspective view thereof;
FIG. 3 is a front elevational view thereof; the rear elevation opposite thereto being identical;
FIG. 4 is a side elevational view thereof; the side opposite being identical thereto;
FIG. 5 is a top plan view thereof;
FIG. 6 is a bottom plan view thereof; and
FIG. 7 is a cross-sectional view taken along line 7—7 of FIG. 5.
